(57) CLAIM

The ornamental design for a hair styling device, as shown and described.

DESCRIPTION

FIG. 1 is a perspective view of a hair styling device showing my new design;

FIG. 2 shows a front side view thereof;

FIG. 3 shows a rear view thereof;

FIG. 4 shows a left side view thereof;

FIG. 5 shows a right side view thereof;

FIG. 6 shows a top plan view thereof; and,

FIG. 7 shows a bottom plan view thereof.

The shade lines in the Figures show contour and not surface ornamentation.

The broken lines shown in the Figures show portions of the hair styling device which form no part of the claimed design.

1 Claim, 4 Drawing Sheets
